UNITED STATES PATENT OFFICE

HENRY M. NICHOLLS, OF CHICAGO, ILLINOIS, ASSIGNOR TO AMERICAN CAN COMPANY,
OF NEW YORK, N. Y., A CORPORATION OF NEW JERSEY

CONTAINER SUPPORT

Application filed June 23, 1928. Serial No. 287,787.

My invention relates in general to improved container supports and more particularly to a collapsible and foldable rack or easel for the pivotal mounting or suspension of large, heavy oil cans or drums, which may be tilted or swung to pouring or dispensing position to withdraw their contents in small quantities without having to lift the container for each withdrawal.

10 While my invention was developed principally for use in connection with five gallon oil drums, the contents of which are dispensed in public and private garages, filling stations and automobile accessory and repair shops, it has a much wider range of utility and may also be employed in connection with paint and varnish containers, containers for molasses and syrups and containers for a variety of other liquid products. My invention may also be adapted to containers for 15 granular and other freely flowing dry substances.

A principal object of my invention is the provision of an improved container support 20 which is of simple and economical construction, which can be manufactured and sold at a reasonable price and which is strong and durable and of neat and pleasing appearance.

25 Another important object of my invention is the provision of an improved container rack which not only securely supports and suspends a filled container but also permits the same to be pivotally tilted or swung to dispensing or pouring position at any desired angle in either direction.

Still another advantage of the invention resides in the fact that the rack may be readily assembled to the container without any 30 special tools and also readily disconnected from the container and adapted to be collapsed without disconnecting its own individual parts and may then be folded flat into a package of small dimensions. It may also be reused in connection with other filled containers of suitable construction.

Still another important object of my invention is the provision of an improved supporting frame for tilting dispensing containers which may be assembled to a heavy filled

35 container by merely moving it from upright to transverse position, springing the pivot pins of the frame into the pivot ears of the container and then using part of the frame as a fulcrum for lifting the container to suspended position.

40 A still further feature of my invention is the embodiment of a display panel which also functions as a brace or reinforcing member for the support.

45 Numerous other objects and advantages of the invention will be apparent as it is better understood from the following description, which, taken in connection with the accompanying drawings, discloses a preferred embodiment thereof.

50 Referring to the drawings:

55 Figure 1 is a perspective view showing the collapsible rack and a suspended container in fully assembled relationship;

60 Fig. 2 is a perspective view of the rack alone showing it disconnected from the container and in partially collapsed position;

65 Fig. 3 is an enlarged cross-sectional view showing the connection between the front and rear wire frame members and the pivotal connection of the former with a pivot ear of the container;

70 Fig. 4 is an elevation, partly in full lines and partly in dotted lines, showing the assembly of the rack with the container and the lifting of both to upright suspended position;

75 Fig. 5 is a top plan view looking down upon the full line part of Fig. 4, but before the supporting frame pins have been inserted into the container pivot ears, and

80 Fig. 6 is a fragmental top plan view of the rack showing the free or extended position of the rear frame member in dotted lines.

85 To illustrate my invention, I have shown on the drawings a preferred embodiment of my collapsible container rack in connection with a well-known type of oil can or drum, which latter comprises a cylindrical body 11 necked in adjacent its top at 12 and having a bottom end 13 and a top end 14 double seamed or otherwise permanently secured thereto.

90 The top 14, inwardly of its double seam

100

connection with the body 11, is formed to provide a sunken panel 15 at the center of which is arranged a wire handle or loop 16, which is held in position by a plate or clip 17 soldered, welded or otherwise secured to the panel 15. Off center and in close proximity to a portion of the annular double seam of the top 14 is a pouring nozzle 18. It is customary to locate the pouring opening or nozzle of a container of this type near an edge or corner of the container in order to bring the opening or nozzle as close as possible to the receptacle which is to receive the contents, to facilitate pouring and to more completely drain the container of its contents. These details of the construction of the container are unimportant to an understanding of the present invention and further description of them is therefore not undertaken.

On opposite points of the container body 11 and somewhat above its center of gravity, the container body 11 is provided with pivot ears or bearings 19 permanently secured thereto. The two sets of ears 19 being of identical construction, only one set (shown in Figure 1) need be described.

This pivot ear 19 is preferably stamped out of a flat piece of sheet metal and comprises a cup-shaped central part with a pivot hole 21 and two wing parts 22, which latter are permanently attached to the container by soldering, welding or any other suitable manner.

The collapsible and foldable rack or supporting frame comprises in general a front wire member 23, a rear wire member 24, two base plates 25 and 26 and a front display panel and reinforcing member 27.

Both front and rear wire members are made from heavy gauge wire or rod which is slightly resilient and yet strong enough to support a very heavy, filled oil drum or the like, without bending under its weight.

The front wire member 23 consists of a transverse, straight, central part 28 which terminates at both ends in downwardly extending parts 29 which in turn merge into two horizontal pivot parts or feet 30 at substantially right angles to the parts 29 and parallel with the transverse, central part 28.

At points of bend 31, the front wire member 23 is bent at right angles into long, upwardly and inwardly slanting, straight supporting arms 32, which terminate adjacent their upper extremities into transverse pivot pins 33. These pins 33 are bent at substantially right angles to the supporting arms 32.

The rear wire member 24 has a central part 34, downwardly extending parts 35 and transverse pivot parts or feet 36 of the same length and bent at the same angles as the parts 28, 29 and 30 of the front wire member 23. At points of bend 37, the rear wire member 24 is bent into a pair of long, up-

wardly and inwardly slanting, straight supporting arms 38 which meet the arms 32 at an acute angle in tripod fashion and at the transverse pins 33. The end of each arm 38 is provided with an eye or loop 39 through which the pin 33 of the companion arm 32 is inserted.

The base plates 25 and 26 are identical in construction and are made from long, rectangular pieces of heavy sheet metal. They have their ends wrapped around the transverse pivots or feet 30 and 36 and preferably the material of their longitudinal center is raised from the plane of the flat part of the plates to form reinforcing ridges or beads 40. The function of these base plates 25 and 26 is to hold the front and rear members 23 and 24 in permanently assembled relationship and to permit these members to be pivotally collapsed and folded, one on each horizontal face of the plate.

The display panel 27 is made from a flat sheet of metal having a central, substantially rectangular part 41 defined by a pair of long, parallel sides 42 and 43 and a pair of short, parallel sides 44 and 45. The material of the panel adjacent the short sides 44 and 45 is extended to form side wings 46 and 47. The extreme side edges of these wings are wrapped around the lower portions of the frame members 32 of the front wire member 23. The metal of the lower, long side edge 43 is also wrapped around the central, straight part 28 of the front wire member 23. It will thus be seen that the panel 27 performs a double function; that is, it presents a smooth, even front face which lends itself very nicely to painting, lithographing or printing advertising matter thereon, and it also reinforces the front wire member 23 by embracing and holding together the parts 28 and 32 of the same.

Reference is now made to Figs. 4, 5 and 6 of the drawings. When it is desired to mount a filled container onto the supporting frame of my invention, the frame members or arms 32 and 38 are first assembled with each other by inserting the pins 33 of the members 32 into the loops 39 of the members 38, as shown in Fig. 6. The dotted lines in Fig. 6 show the position which members 38 assume before their assembly with the members 32; that is to say, this view clearly illustrates that prior to this connection the members 38 are arranged outside the members 32 and must be pressed inwardly as an incident to assembly. The assembled frame is then moved from upright toward a horizontal position (illustrated in Figs. 4 and 5) until the pivot pins 33 come within a short distance of the pivot ears 19 when the pairs of assembled members or arms 32 and 38 must be spread so that the pins 33 may be inserted into the pivot holes 21, as illustrated by full lines in Fig. 4. When both sides of

the supporting frame have thus been assembled to the container, the latter may then be grasped by the handle 16 and by using the edge 48 of the frame as a fulcrum, the container and frame may be brought to upright position (shown in dotted lines in Fig. 4) with very little exertion.

In collapsing and folding the supporting frame for temporary storage or shipment, 10 the front wire member 23 is swung outward and downward and folded with the flat panel 27 against the under sides or flat faces of the base plates 25 and 26, and the rear wire member 24 is swung forward and inward, and 15 when completely folded the frame members 38 will lie one alongside the base plate 25 and the other alongside the base plate 26. The whole framework thus folds into a compact, flat package of small dimensions and is 20 adapted to be easily and economically handled for storage and shipment.

The container, framework and panel may be decorated in a variety of colors to present a very attractive and pleasing appearance.

It is thought that the invention and many of its attendant advantages will be understood from the foregoing description, and it will be apparent that various changes may be 30 made in the form, construction and arrangement of the parts without departing from the spirit and scope of the invention or sacrificing all of its material advantages, the form hereinbefore described being merely a 35 preferred embodiment thereof.

I claim:

1. In a collapsible supporting rack for containers, in combination, a front wire member, a rear wire member, said front and rear members being each bent to form supporting arms and transverse parts, and a pair of base members having pivotal folding connections with said transverse parts, one of said wire members being bent to form pivot parts 45 adapted to engage complementary pivot parts of a container to mount the latter and to permit it to be tilted to pouring position at any angle and the other of said wire members having eyes to engage said pivot parts.
2. In a collapsible supporting rack for containers, in combination, a front wire member having pivot pins, and a rear wire member having eyes and being resilient so that said pins may be passed through said eyes, 55 and transverse parts connected with said members on axes of folding, said pins being also adapted to engage complementary pivot parts of a container to mount the latter and to permit it to be tilted to pouring position at any angle, said wire members being foldable together when said pins are withdrawn from said eyes.

3. In a collapsible supporting rack for containers, in combination, a pair of wire rods 5 each having its ends bent at right angles to

its center, said rods being arranged to dispose the ends of one rod in angular relation to the ends of the other and said ends being engaged at their meeting points to provide a triangular support at each side for a container, the connection between said ends comprising eyes upon one rod and pins upon the other rod passing through said eyes, and means foldably connecting said rods, the latter being foldable when the ends of said rods are disengaged from each other.

4. In a collapsible supporting rack for tiltable containers, the combination of a pair of supporting frames each of which is bent to form pivot feet and supporting arms and transverse parts connecting said arms of each frame, a reinforcing panel bent around one of said transverse parts and around the supporting arms thereof, and base plates pivotally connecting said feet of one frame with the feet of the other frame, said arms having pivoting means at their upper ends for engaging pivot bearings of a container.

5. In a collapsible supporting rack for tiltable containers, the combination of a pair of supporting frames each of which is bent to form pivot feet and supporting arms and transverse parts connecting said arms of each frame, and base plates pivotally connecting said feet of one frame with the feet of the other frame, said arms having pivoting means at their upper ends for engaging pivot bearings of a container, said pivoting means at each side of the rack consisting of an eye on one of said arms and a pin on the other of said arms, said pin being adapted to engage said eye and a pivot bearing of the container.

HENRY M. NICHOLLS.
